UNITED STATES PATENT OFFICE

2,420,663

WATER-COOLED AMMUNITION RACK

Louis T. Heath and Vincent C. Gilbert,
Fort Knox, Ky.

Application July 15, 1944, Serial No. 545,169

2 Claims. (Cl. 220—13)

(Granted under the act of March 3, 1883, as
amended April 30, 1928; 370 O. G. 757)

1

The invention described herein may be manufactured and used by or for the Government for governmental purposes, without the payment to us of any royalty thereon.

The present invention pertains to a novel water-cooled ammunition rack designed particularly for use on combat tanks but also useful in other installations.

The object of the invention is to provide an ammunition rack so constructed as to reduce the danger of fire and explosion when the rack is struck by a projectile. The device consists generally of a number of spaced ammunition-receiving tubes supported in and sealed from a water-tight container. When the container is filled with water, the receiving tubes are surrounded by water. Each tube has an exposed open end through which a round of ammunition can be passed.

A striking projectile, on rupturing a powder shell, immediately exposes the powder to the water. Also, hot fragments produced and thrown into the receptacle by the impact are immediately cooled by the water. The danger of fire and explosion from either cause is thus materially reduced or entirely eliminated.

In a more developed form of the invention, a cylindrical wall is formed around each of the tubes in spaced, concentric relation thereto. The annular space between each wall and the tube therein is filled with water while the remaining space in the container is not filled. Two advantages result from this construction. A projectile striking the container does not create an excessive hydrostatic pressure throughout the container, and the rupturing of one or more cylindrical walls does not drain the water from the undamaged units.

An illustrative embodiment of the invention is disclosed in the following description and in the accompanying drawing in which:

Figure 1 is a plan view, partly in section, of a vertical rack; and

Figure 2 is a vertical section thereof.

The rack is mounted, for example, on a combat tank by fastening to the armor plate thereof. Other installations will be obvious. The rack includes a box-like, water-tight structure 1 consisting preferably of armor plate and of the desired size and shape. The structure 1 is provided in its top with one or two pipe fittings 2 provided each with a screw cap 3. One of the walls 4, preferably the top, of the box is formed with a number of openings 5 from each of which extends a tube 6, preferably cylindrical, to the

2

opposite wall 7. The ends of the tubes are suitably secured, as by welding, to the opposite walls 4 and 7. Each tube is designed to receive a round of ammunition 8 through the opening 5, as illustrated in Figure 2.

A cylindrical wall 12 is mounted around each tube 6 in spaced concentric relation thereto, the corner tubes constituting the corners of the box structure 1. The walls 12 terminate short of the top of the container 1 and are interconnected by a sealing plate 13 which however does not cross the annular chambers 14 between each wall 12 and the tube 6 therein. An air space 15 is thus formed in the top of the device. The filling and vent necks 2 mounted in the top of the container communicate through the space 15 with the chambers 14.

In the use of the device, the container 1 is filled with water through one of the fittings 2, while the other serves as a vent. The same system may be used for flushing when desired. The tubes 6 are sealed from the interior of the container and thus receive no water. One of the lateral walls of the container may have an overflow port 16 near the top 4 to provide an air space 17 over the water for reducing the hydrostatic pressure when the device is struck by a projectile.

30 A projectile penetrating the box 1 and striking a tube 6 ordinarily has sufficient force to rupture the tube and the case of the ammunition round therein. The impact of the projectile also produces spalls of armor which enter the container 1 and may penetrate the cases and the powder therein. The entire structure of the ammunition rack is usually disrupted, and the released water cools the hot armor fragments and the projectile and also wets the powder, thus preventing ignition from contact with hot armor spalls. In the disruption of the ammunition rack, water is thrown over the entire wreckage, thereby wetting and cooling the surrounding area and quenching any powder that may have become ignited.

45 The unfilled spaces external of the walls 12 prevent the formation of excessive hydrostatic pressure on impact by a projectile. Also, any walls 12 that may remain undamaged are not drained of their water content.

50 While a specific embodiment of the invention has been shown and been described, it will be understood that various alterations may be made without departure from the spirit of the invention as indicated by the appended claims.

What we claim is:

1. An ammunition rack comprising a unitary, box-like, water-tight container having walls at the sides, top and bottom thereof preferably of armor plate, a filler fitting in said top wall to permit the flow of liquid into said container, spaced openings in said top wall, vertically extending ammunition-receiving tubes supported in and sealed from said container, each of said ammunition-receiving tubes being sealingly attached at one end thereof to said top wall at said openings and at the other end thereof to said bottom wall, the top ends of said ammunition-receiving tubes being open through said openings in said top wall, a sealing plate inside said container spaced laterally from and substantially parallel to said top wall and extending to said side walls, said sealing plate having cutout portions corresponding to said openings in said top wall but of a size substantially larger than the diameter of said ammunition-receiving tubes which pass therethrough, and vertically extending sleeves surrounding said ammunition-receiving tubes and spaced therefrom inside said container, each of said sleeves being sealingly attached at one end thereof to said sealing plate at said cutout portions and at the other end thereof to said bottom wall; the top ends of said sleeves being open through said cutout portions in said

sealing plate to the common space between said sealing plate and said top wall.

2. An ammunition rack as set forth in claim 1 wherein an aperture is provided in one of said side walls of said container between said sealing plate and said top wall for providing an air space in at least a portion of said common space between said sealing plate and the top of said container, whereby liquid pressure is reduced when said container is struck by a projectile.
